(57) **CLAIM**

The ornamental design for a ground decking panel, as shown and described.

DESCRIPTION

FIG. 1 is a top plan view of a ground-decking panel showing the new design;

FIG. 2 is an underside plan view thereof;

FIG. 3 is a first side view thereof;

FIG. 4 is a second side view thereof;

FIG. 5 is a first fragmentary perspective end view thereof; FIG. 6 is a second fragmentary perspective end view thereof; FIG. 7 is a fragmentary perspective view of the ground-decking panel which includes additional ramp and plug components, shown separated;

FIG. 8 is a fragmentary perspective view of the embodiment shown in FIG. 7, also including additional ramp and plug components, joined in a first possible configuration;

FIG. 9 is a fragmentary perspective view of the embodiment shown in FIG. 7, also including additional ramp and plug components, joined in a second possible configuration;

FIG. 10 is a first perspective view of the additional ramp and plug components, separated; and,

FIG. 11 is a second perspective view of the additional ramp and plug components, separated.
